INDICATOR POINTER FOR FLIGHT INSTRUMENT

John Peter Dietrich, Glendale, Ariz., assignor to Sperry
Rand Corporation, New York, N.Y.

Filed Mar. 27, 1974, Ser. No. 455,483

Term of patent 14 years

Int. Cl. D10—07

U.S. Cl. D10—127

FIG. 4.

FIG. 2.

FIG. 3.

FIG. 1.

FIG. 1 is a front elevational view of an indicator pointer for flight instrument showing my new design, it being understood that the rear is a mirror image thereof;

FIG. 2 is a top plan view thereof;

FIG. 3 is a right end elevational view thereof; and

FIG. 4 is a front elevational view thereof to a reduced scale in the environment of a flight instrument which is shown in broken lines for illustrative purposes only.

I claim:

The ornamental design for an indicator pointer for flight instrument, as shown and described.
